ATTORNEY.

UNITED STATES PATENT OFFICE.

CHARLES T. PRATT, OF FRANKFORT, NEW YORK.

DESIGN FOR A SLIP-NIPPLE.

SPECIFICATION forming part of Design No. 29,797, dated December 13, 1898.

Application filed October 26, 1898. Serial No. 694,636. Term of patent 14 years.

To all whom it may concern:

Be it known that I, CHARLES T. PRATT, a citizen of the United States, and a resident of Frankfort, in the county of Herkimer and State of New York, have invented and produced a new and original Design for Slip-Nipples, of which the following is a specification, reference being had to the accompanying drawings, forming a part thereof.

10 The slip-nipple is more particularly intended for use in radiator constructions.

Figure 1 shows a perspective view of a slip-nipple of my design. Fig. 2 shows a side elevation of the same. Fig. 3 shows a section taken on the central line of the nipple. Fig. 15 4 shows a longitudinal section taken on a line with A B of Fig. 3. Fig. 5 shows a longitudinal section taken on line C D of Fig. 3.

The leading feature of the design is the tubular form or shape of the body of the nipple, swelled between its ends and having a series of elongated projections 2 arranged in a line around the middle portion of the nipple, as shown. 20

Having described my invention, what I 25 claim as new, and desire to secure by Letters Patent, is—

The design for a slip-nipple as herein shown and described.

In witness whereof I have hereunto set my 30 hand, in the presence of two witnesses, this 17th day of October, 1898.

CHARLES T. PRATT.

Witnesses:

E. WILLARD JONES,
VIOLETTA PARKER.
